(57) **CLAIM**

The ornamental design for a gas analyzer, as shown and described.

DESCRIPTION

1. Gas analyzer
- 1.1 : Perspective
- 1.2 : Front
- 1.3 : Back
- 1.4 : Left
- 1.5 : Right
- 1.6 : Top
- 1.7 : Bottom

The broken lines do not form part of the claimed design; the dotted-dashed lines indicate the boundary between the claimed area and the unclaimed area.
